UNITED STATES PATENT OFFICE.

PHILIP HOWARD COLOMB, OF FULHAM, COUNTY OF MIDDLESEX, ENGLAND.

IMPROVEMENT IN APPARATUS FOR SIGNALING.

Specification forming part of Letters Patent No. 43,763, dated August 9, 1864.

To all whom it may concern:

Be it known that I, PHILIP HOWARD COLOMB, formerly of Her Majesty's Dockyard, Devonport, in the county of Devon, lieutenant in the Royal Navy, and now of Fulham in the county of Middlesex, Kingdom of Great Britain and Ireland, commander in the Navy of Her Britannic Majesty, have invented certain new and useful Improvements in Arrangements and Apparatus for Signaling; and I do hereby declare the following to be a full, clear, and exact description of the same, reference being had to the accompanying drawings, and to the letters of reference marked thereon.

This invention is applicable for the purpose of communicating signals between vessels at sea and the shore, and for signaling from one position to another upon land, whether the latter be for military or other purposes. The principle of its action consists in the employment, for night-signals, of flashes of light separated by intervals of darkness, such flashes being of varying duration, and a certain number of long or short flashes, or the combination of a certain number of long with a certain number of short flashes being taken to represent a certain number, letter, or other distinguishing character of any recognized or prearranged code of signals. By the use of long and short flashes of light, as described, I am enabled to make a much greater number of distinct signals with the same number of alternate flashes of light and intervals of darkness and with less liability to errors of observation than if flashes of equal length only were employed. Thus, for some signals I may employ one or more short flashes, for others one or more long flashes. Then one or more short flashes followed by one or more long flashes; or one or more long flashes followed by one or more short flashes, and so on, varying the number, order, and combination of the flashes, and assigning to each number, order, and combination of flashes its particular meaning in the code. In order that the long and short flashes required may be readily and correctly produced and repeated at proper intervals during any length of time, until the same shall have been duly seen and acknowledged from all the ships or stations within sight or range of their influence, I make use of a cylindrical or other formed barrel, or of an endless belt, chain, or other equivalent or suitable arrange-

ment provided with one or more series of pins, projections, depressions, or holes, which, upon the barrel, belt, chain, or other arrangement being caused to revolve or move, either by a winch-handle, or other convenient or suitable means, give motion through levers or other suitable connections to a cover whereby the signal-light is obscured or exposed at proper intervals and for the proper comparative lengths of time to indicate the distinguishing number or marks of the signal represented. Where the signals of a code are distinguished by numbers, I employ (upon or in the barrel, endless belt, chain, or other arrangement) as many series of pins, projections, depressions, or holes as there are figures in the highest number of the code. Each of these series consists of ten distinct rows or sets of pins, projections, depressions, or holes, the first one being calculated to act upon the cover of the signal-light so as to make the signal 1, the second to signal 2, and so on up to 9, and the remaining set to make the signal 0. The several series are arranged so that one series will have passed out of action, leaving a marked space of time before a second series will have commenced acting. If it be now understood that the several levers or other parts appertaining to each series of pins, projections, depressions, or holes, and intended for conveying motion to the cover of the light, can be placed so as to be acted upon by any one of the ten sets of each series, it will be easily seen that any number not comprising a greater number of figures than the machine is calculated for may be readily signaled, and that it will only be necessary to continue the machine in motion in order to continually repeat the signal. Thus, supposing the number to be signaled is 394, one lever or other connection (whereby motion is given to the cover) is placed so as to be acted upon by set 3 of the first series, another by set 9 of the second series, and a third by set 4 of the third series. It is obvious that on now working the machine the signal 394 will be continually repeated as long as the working continues. The machine may in like manner be arranged to suit any other kind of code or system of signals, or, if found desirable, it may be made capable of working either of two or more codes or systems, or a code or system and various special signals, as required. For day-signals, the same system of apparatus

may be modified and arranged, so as to regulate the opening and closing of suitable shutters or doors, the expansion and contraction or collapse of large balls or cones, or other easily-seen movement or movements of any suitable forms or bodies.

In order to enable others skilled in the art to make and use my invention, I will now proceed to describe its construction and operation.

Figure 1, Sheet 1, of the accompanying sheets of drawings (which form a part of this specification) is a general plan of one arrangement of the machine I employ for the purpose of giving motion to the cover of the signal-light at proper intervals, as hereinbefore explained; Fig. 2, an end elevation of the same, partly in section, having a portion of the framing removed for the purpose of more clearly showing the several working parts; and Fig. 3, an elevation of the contrary end of the machine, showing the levers to be connected with and employed for giving motion to the cover of the light, as further illustrated at Fig. 4, which represents a similar view of the machine, drawn to a reduced scale, and shows the manner in which the levers are connected with the cover. Figs. 5 and 6 represent the system of projections made use of for producing various signals.

The same letters of reference are made use of to identify the same parts in all the views.

The working-barrel *a* of the machine is fixed upon a shaft, *b*, supported and free to revolve in bearings formed in the end framing, *c*, of the machine. Upon the shaft *b* is also keyed a worm-wheel, *d*, actuated by a worm, *e*, formed upon the shaft *f*, working in bearings at *f'*, and capable of being caused to revolve by means of the winch handle *g*.

Upon the barrel *a* are five series of projections, *h*, *h'*, *h²*, *h³*, and *h⁴*, the series *h* intended to act upon the lever arrangement for signaling the unit figures, the series *h'* to act in like manner for signaling the tens, the series *h²* for the hundreds, and the series *h³* for signaling thousands. The remaining series, *h⁴*, in like manner actuates the levers so as to make any required one out of the special signals, to each of which is assigned a particular significance, according to the code adopted.

In front of the barrel *a*, and parallel to its axis, is a square shaft, *i*, supported in bearings formed in the framing *c* and carrying levers *j*, *j'*, *j²*, *j³*, and *j⁴*, capable of being moved into various positions along its length, and having jointed to them the pieces *k*, *k'*, *k²*, *k³*, and *k⁴*, which take into notches formed in the flat bar *l*, and are held therein by springs *m*, attached to the levers *j*. Upon the end of the shaft *i* (which is capable of partial rotation in its bearings) is fixed a lever, *n*, jointed by a link at *o* to another lever, *p*, having its fulcrum at *p'*, to which is attached the cord *q*, passing over pulleys *q'*, as shown at Fig. 4, and carrying the cover *r*, whereby the light of the signal-lamp *s* is obscured. Each of the

notches in the bar *l* is situated opposite to one of the rows of projections upon the barrel *a*, and each notch is numbered to correspond with the signal to be produced by the row of projections to which it is opposite. This being understood, and also that the four series of numbers represent, respectively, units, tens, hundreds, and thousands, the action of the machine will be easily understood.

In the code of signals for which the machine is arranged the numeral 1 is represented by one short flash or exposure of the light; 2, by two such short flashes; 3, by three such short flashes; 4, by four such short flashes; 5, by five such flashes; 6, by one long flash or exposure of the light; 7, by one short followed by one long flash; 8, by one long followed by one short flash; 9, by two short succeeded by one long flash; and the cipher 0, by one long succeeded by two short flashes. Now, let it be required to signal the number 394. The piece *k²*, which is jointed to the lever *j²*, is pulled backward out of the notch wherein it is shown, and the lever is moved along the shaft *i* to the notch 3 of the series *h²*, as shown in red lines. The lever *j'* is in like manner moved into the position 9 of the series *h'*, and the lever *j* into the position 4 of the series *h*, as likewise shown in red. The levers *j³* and *j⁴* not being required, remain out of action, as shown. On the barrel being now caused to revolve in the direction of the arrows, the three projections opposite to notch 3 of the series *h²* will successively come into contact with the lever *j²*, thereby depressing it three times, and at each depression raising the cover *r*, and as often momentarily exposing the light of the lamp *s* and making the signal 3 as required. The circumference of the barrel *a* being divided into equal divisions, each occupied by one series only of projections, a marked interval will now elapse during which the rotary movement of the barrel will leave the cover *r* undisturbed. This interval marks the termination of the flashes representing the first figure of the signal. The continued revolution of the barrel then successively brings the three projections representing 9 of the series *h'* into contact with the lever *j'*. Two of these projections being short and the third of considerable length, successively act upon the lever *j'*, thus raising the cover *r* and exposing the light during three corresponding periods of time, thus signaling the second numeral required. A marked interval then again occurs before the rotation of the barrel brings the projections 4 of the series *h* into action upon the lever *j* for making the signal 4, which, consisting of four short flashes, is made by a corresponding number of short projections upon the barrel. The levers *j³* and *j⁴*, not being required for the signal made, are kept out of action by notches so situated that the ends of the levers are clear of the course of any of the projections.

It will be obvious to any competent mechanic that the projections made use of in the machine described for acting upon the cover of

the lamp may be substituted by depressions or holes, as also that a belt or chain, formed or provided with suitable projections, depressions, or holes, may be employed instead of the barrel for giving motion to the cover.

In Sheet 2 are represented some arrangements which may conveniently be employed for day-signaling in connection with the before-mentioned apparatus. In these cases the flash of the night-signal is replaced by the display of a conspicuous opaque figure, the appearance and total or partial disappearance of which is regulated by the working of the apparatus in the same manner as the raising of the cover of the light is regulated for the purpose of night-signaling.

The arrangement represented by Figs. 1, 2, 3, and 4 consists of a series of shutters or boards, *t*, turning upon centers, so as to be capable of being set either edgewise or with their sides toward the observer.

Fig. 1 is a front view showing the shutters open or presenting their edges to the observer; Fig. 2, a section through the line A of Fig. 1; Fig. 3, a front view showing the shutters closed, and Fig. 4 a section through the line B of Fig. 3.

In order to work the shutters, the cord *g*, attached to the lever *p* of the machine, is in this case connected with a bar, *u*, whereby its movement is communicated to the shutters, so as to close them and thus render the signal-disk distinctly visible at each depression of the lever *p*. The reopening of the shutters is effected by a spring which acts upon and raises the bar *u* the moment it ceases to be held down by the lever *p*.

Figs. 5 and 6 represent a hollow cone formed of sail cloth or other suitable material, and so arranged as, in its normal position (shown at Fig. 5) to present only a comparatively small surface, but when expanded or drawn out, as at Fig. 6, to be clearly visible at a considerable distance.

The drawing out or elongation of the cone, which answers to the exposure of the light in the night-signals, is effected by the cord *g*, attached to the lever *p*, as the closing of the shutters was in the previous arrangement.

Figs. 7 and 8 represent an arrangement having the form of a fan, which, when closed, appears as at Fig. 7, but when opened by the action of the cord *g* (attached to the lever *p*, as before) takes the form represented by Fig. 8.

Figs. 9 and 10 are corresponding views of an arrangement of semaphore, (which may be suspended or fixed in any convenient situation,) the arms of which hang down, as at Fig. 9, but by the drawing down of the cord *g* are instantly thrown out horizontally, as shown at Fig. 10.

Figs. 11 and 12 represent a kind of bellows-formed collapsible drum, the normal position

of which is as at Fig. 11, but which on being acted upon by the cord *g* is expanded to the form shown at Fig. 12.

Figs. 13 and 14 represent a frame, on which a flag or banner is displayed by the drawing down of the cord *g*.

I am fully aware that long and short flashes or exposures of light, and long and short indications of other kinds, have been used by others for signaling purposes prior to the date of the Letters Patent of the United Kingdom of Great Britain and Ireland, the Channel Islands and the Isle of Man, granted to me and bearing date the 7th day of May, in the year of our Lord 1862; and I do not lay claim to the first invention of such long and short flashes or indications for those purposes.

The novelty of my invention consists in the employment of a means as or substantially similar to that described for producing any required series or succession of such long and short flashes or indications, and for repeating the same over and over again as often as may be found necessary or desirable; and

What I claim as my invention, and desire to secure by Letters Patent, is—

1. The use for night-signaling of a light or lights shown or exposed during varying periods of time, regulated as described.

2. The use for day-signaling of an opaque or other clearly visible body or bodies shown or exposed during varying periods of time, regulated as described.

3. The use for the purposes described of a notched bar or other equivalent arrangement for enabling the levers or other connections whereby motion is imparted from the pins, projections, depressions, or holes, to be adjusted so as to be acted upon by the required sets of projections, depressions, or holes, or to be thrown out of action, as required.

4. The employment of levers, or equivalent parts, adjustable endwise upon an angular or other bar, for the purpose of imparting the motion received from the projections, depressions, or holes, so as to regulate the appearance and disappearance or expansion and contraction or change of position or form of the signaling object or objects.

5. The use of a drum, endless belt, chain, or equivalent arrangement, provided with projections, depressions, or holes, and capable of being driven with a continuous motion for the purpose of regulating the appearance and disappearance, expansion and contraction, or change of position or form of figures or objects used in signaling.

In testimony whereof I have signed my name to this specification in the presence of two subscribing witnesses.

P. H. COLOMB.
